(57) **CLAIM**

The ornamental design for an animated image for a portion of a display screen, as shown and described.

DESCRIPTION

FIG. 1 is a first image in the sequence for an animated image for a portion of a display screen showing our new design;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The appearance of the animated image sequentially transitions between the images shown in FIGS. 1–6. The process or period in which one image transitions to another forms no part of the claimed design.

The broken line showing of the portion of a display screen, and the elements within the animated image forms no part of the claimed design.
